CLAIM

I claim, the ornamental design for a workstation luminaire, as shown and described.

DESCRIPTION

FIG. 1 is a perspective view of a workstation luminaire showing my new design;

FIG. 2 is a front elevation view thereof; and,

FIG. 3 is a side elevation view, the opposite side being a mirror image hereof.

The break lines shown in FIGS. 1 and 2 drawings views represent indeterminate length.

1 Claim, 2 Drawing SheetsFIG. 1

FIG. 2

FIG. 3
